[57] **CLAIM**

The ornamental design for a combined medication dispenser and cassette, substantially as shown and described.

DESCRIPTION

FIG. 1 is a perspective view of a combined medication dispenser and cassette showing my new design in the open condition to expose the arrangement of the cavities covered by a transparent inner lid having corresponding depressed portions into each cavity;

FIG. 2 is a perspective view as in FIG. 1 with the cassette removed;

FIG. 3 is a bottom plan view thereof;

FIG. 4 is a perspective view of the cassette removed and in open condition; and

FIG. 5 is a cross sectional view taken along line 5—5 of FIG. 2 showing the arrangement of the depressions of the transparent inner lid into each cavity.

FIG. 1

FIG. 3

FIG. 4
